UNITED STATES PATENT OFFICE

2,554,860

HEAT SEAMER

James M. Humphrey, New Richmond, Wis., assignor to Doughboy Industries, Inc., New Richmond, Wis., a corporation of Wisconsin

Application December 11, 1946, Serial No. 715,576

2 Claims. (Cl. 154—42)

1

This invention relates to heat sealing machines which can be freely transported and easily installed, as well as readily employed for applying to thermoplastic sheets or other bodies the desired amount of heat and pressure for uniting the same.

The invention relates more particularly to a heat seamer or a machine by means of which joints between sheets or other bodies may be made under the influence of controlled heat and pressure and with or without the use of a binding strip.

Prior machines employed in the art of sealing or joining by the application of heat and pressure have been unsatisfactory for various reasons including their cost, size, weight and complexity of both structure and operation requiring a skilled person to operate, and were also lacking in certain essential or desirable features.

It is an object of the invention to provide a simple, inexpensive, practical, heat seamer of relatively light weight and small size, which can be used to efficiently and satisfactorily join sheets or bodies with or without employing a joining or binding strip in the joint, and in which the joint will be of the desired strength and pleasing appearance.

Another object of the invention is to provide a seamer with mechanism for relieving the pressure between the sealing rolls when the material is between the rolls and is not being advanced, such mechanism serving to prevent injury to such material.

A further object of the invention is to provide a machine which can be operated continuously or intermittently with facility similar to the operation of a conventional sewing machine in order to accomplish the necessary or desired operations.

Briefly stated, the invention comprises cooperating intermeshing temperature and pressure controlled heat rolls mounted on horizontal axes adjacent a work table having conveyors thereon for sheets or the like to be joined as they are carried along the table. Also, there is provided structure for applying a solvent to a tape and for folding the tape around remote sides of the material as it passes between the heat rolls so that the joining operation is limited to that between the sheets and the strip and with no direct sealing together of the contacting surfaces of the sheets themselves. The invention likewise includes variable driving mechanism for controlling the speed of the heated rolls as desired or in accordance with requirements.

The machine additionally includes an appli-

2

cator of felt or other suitable capillary material for applying solvent in liquid form to the tape as well as retracting means for spacing the tape and the applicator when the tape is stationary in the machine so that the solvent does not act on the tape excessively.

In order to make the machine more flexible so that different pressures may be employed in joining materials of different characters and thicknesses, an adjustable weight or lever is employed for exerting pressure on one of the bearings of the rolls and with an elevating member to relieve the pressure of the weight and also the weight on the bearing.

15 Further objects and advantages of the invention will be apparent from the following description taken in conjunction with the accompanying drawings, wherein:

Fig. 1 is a top plan view;

Fig. 2, a rear elevation;

Fig. 3, a horizontal section on the line 3—3 of Fig. 2;

Fig. 4, a detailed perspective of the tape folder;

Fig. 5, a fragmentary perspective of the folder and sealing roll;

Fig. 6, an isometric view of the solvent tank and dispenser;

Fig. 7, a diagrammatic view of the linkage for controlling the contact between the tape and the solvent applicator;

Fig. 8, a diagrammatic view of the linkage for controlling the operation of the pressure applying means on the upper sealing roll;

Fig. 9, a side elevational view with parts in vertical section illustrating the pressure applying mechanism for the upper sealing roll;

Fig. 10, a fragmentary vertical section taken on the line 10—10 of Fig. 1;

Fig. 11, a detail of the sealing rolls illustrating particularly the heat control means; and

Fig. 12, a wiring diagram of the electrical circuit employed in the machine.

With continued reference to the drawings, upper and lower sealing rolls 10 and 11 are mounted, 45 respectively, on shafts 12 and 13 disposed one above the other in suitable bearings 14 in brackets 15 and 16 carried by longitudinal bars 17 and 18 supported on transverse bars 17' and 18' which are in turn supported by front and rear longitudinal frame members 19 and 20, respectively. These rolls 10 and 11 are provided with heating elements 21 and a heat controller 22, as disclosed in my Patent 2,376,253 of May 15, 1945.

In order to vary the pressure between the rolls 55 the anti-friction bearing 14 which supports the shaft 12 on which the upper roll is mounted is ver-

tically slidable in a slot 23 in the bracket 16 which forms in effect a retaining guide for the bearing.

A lever 24 is pivoted on a post 25 of the bracket 16. This lever is provided with spaced notches 26 for the selective reception of a weight 27 in order to provide the necessary variation in pressure on the bearing 14 and the shaft and supported upper roll. This is accomplished through the medium of a pin 28 slidably mounted in a substantially vertical bore 29 above the axis of the shaft 12 beneath the lever 24 and near the pivoted end of the lever. The shafts 12 and 13 are of sufficient length to space the rolls 10 and 11 a substantial distance from the bracket 16 in order to provide an enlarged throat to afford room for the material being processed.

A work table 30 is disposed transversely of the roll shafts 12 and 13 and is provided with spaced grooves 31 disposed lengthwise along the top of the table and which constitute runways for conveyor belts 32 which extend around pulleys 33 fixed on front and rear shafts 34 and 35 respectively, disposed one at each end of the table.

A sprocket 36 on the shaft 35 at the discharge end of the table is driven by a chain 37 from a sprocket 38 on the lower feed roll 11 and the upper run or this chain is retained in a substantially straight line by means of an idler 39 which engages the bottom run of the chain, such idler being carried by a bracket 40 mounted on the rear frame member 20. While a chain is described, a belt of other character may be employed. The upper surface of the upper run of the chain 37 is disposed in substantially the same horizontal position as the upper surface of the conveyor belts 32 and accordingly assists in conveying material operated upon toward the discharge end of the table.

A seam binder or tape feeder 41 is employed for feeding tape 42 of thermoplastic material between the rolls so that the tape may be used in forming the joint between upper and lower sheets 43 and 44 respectively also of thermoplastic material under the influence of heat and pressure. The discharge end 45 of the tape feeder is disposed adjacent the entrance to the rolls 10 and 11, and in order to fold the tape 42 the tape feeder 41 is folded upon itself so that its intermediate portion is remote from the table and its sides are disposed in opposition to each other toward the table, such sides having their edges turned inwardly to form retaining flanges 46 for the tape. Thus the tape 42 will be fed doubled upon itself between the sealing rolls 10 and 11 and between the portions of which tape 42 the aligned edges of the superposed sheets 43 and 44 to be joined are adapted to be received.

The binder 41 is supported by an arm 47 to which it is secured by means of a pivot bolt 48. The bracket is mounted on the cross member 17.

The tape 42 is fed through the tape former guide 41, and when it emerges from the discharge end 45 of this tape former, the tape is folded upon itself as shown in the lower left hand portion of Fig. 5 and is pressed by the rolls into the compact relation illustrated in the upper left hand portion of this same figure. Sheets 43 and 44 and the tape 42 are of thermoplastic material and can be united by heat and pressure. However, it has been found that a satisfactory joint is readily obtainable by the utilization of a solvent between the surfaces desired to be united, and then the united surfaces are subjected to heat and pressure sufficient to cause the parts

to be welded together. The amount of heat and pressure is considerably less when the solvent is used than when it is not used, and when the parts are united with the use of the solvent, the temperature and pressure do not have to be sufficient to effect the integration of the parts without the solvent. A temperature of 170° has been found adequate when the sheets and the tape are of relatively thin material.

The tape 42 is mounted on a holder or reel 49 having a backing disc 50 at one side for limiting the lateral movement of the tape so that it will not accidentally slip from the reel and unwind or become entangled. In opposition to the backing disc 50 at the other side of the reel is a retaining strip 51 which, together with the disc 50, insures the maintenance of the tape on the reel. The strip 51 is secured in place by means of a wing nut 52.

In order to supply a solvent to the tape prior to its entry into the tape former a solvent applicator is provided in the form of a tank 53 having a filling opening 54 at one end and an applicating medium 55 in the form of a capillary material such as felt or the like. By means of this felt or the like liquid is lifted by capillarity and deposited upon the under side of the tape 42 as the tape is caused to advance through the tape feeder.

In the use of the machine interruption of the rotation of the rolls causes the tape to stop advancing and in order to limit the contact of the tape with the tape moistener means is provided for lifting or spacing the tape from the capillary

material. This structure comprises a lifting arm 56 having inwardly projecting opposed sets of guide extensions 57 and 58 through which the tape travels prior to its entry into the tape feeder. Lifting arm 56 is mounted in the shaft 59 jour-

naled in the longitudinal bars 17 and 18. This shaft is held against lateral movement by set collars 60 disposed in spaced relation on the shaft between the bars 17 and 18. The shaft 59 is adapted to be oscillated to cause the arm 56

to move upwardly and raise the tape from contact with the moistener. In order to produce oscillation of the shaft 59 this shaft is provided with an adjustable arm 61 connected by a link 62 on an arm 63 on the shaft 64 provided with a longer arm 65 adapted to be operated by a link 66 from an arm 67 on a treadle shaft 68, such shaft being rotatable by operation of a treadle 69 to be depressed by the foot of the operator. In other words, depression of the treadle 69 lowers the arm 56 into contact with the solvent applicator 55.

Not only is it advisable or desirable to separate the tape from the solvent applicator when the advance of the tape is interrupted, but it is also desirable to release the pressure of the rolls on the tape when the rolls stop rotating, otherwise the heat and pressure of the rolls might damage the tape. Accordingly, the treadle movement which starts and stops the rolls in addition to operating the linkage which causes the lifting arm to elevate the tape from the applicator, is also employed to actuate linkage for raising the arm 24 so that the adjustable weight thereon and associated parts, will be taken off the bearing 14. This includes the link 66 which operates the arm 65, which oscillates the shaft 64, carrying a shorter arm 70 connected by link 71 to an arm 72 on a shaft 73 having on its opposite end an arm 74 which is engaged by an adjusting

screw 75 which threads through a block 76. The

block 76 is attached to the arm 24. With this construction when the treadle is depressed the shaft 73 will be rocked to lower the arm 74 and to permit the downward movement of the weighted arm to cause the pin 28 to apply the weight to the bearing 14, shaft 12, and associated roll 10. Thus when the treadle is depressed when the roll is rotating weight will be applied to the roll and the tape will be supplied with moisture by the applicator.

The frame of the machine which supports the rolls in associated parts is of simple construction and carries on its lower portion a motor 77 for driving the rolls, the conveyor, and other driven parts of the machine. The motor 77 receives its energy directly from the main line through conductors 78 and 79, and the energy to the motor is controlled by means of a motor switch 80, located in convenient position at the front of the machine. Electrical energy for supplying heat to the heating rolls is provided by leads 81 and 82 and controlled by a roll heating switch 83. The conductors or leads 81 and 82 are connected to spring leads 84 and 85 which resiliently engage the peripheries of contact discs 86 and 87 on the roller shaft 12 for heating the roll 10 and a corresponding set of contacts and discs on the lower shaft 13 for completing the circuit through resistors 21 for heating the roll 11, similar to that shown in my previous patent above mentioned. It will be noted that in the wiring diagram of Fig. 12 there is shown a thermostat T for the heating elements 21 of each roll. However, if desired the heating elements 21 may be connected in series and the temperature thereof controlled by a single thermostat. The thermostats T are mounted directly on the sealing rolls in order to respond readily to any changes of temperature therein.

The motor 77 by means of a pulley 88, V-belt 89, and pulley 90 drives a shaft 91 mounted in suitable bearings 92 on the frame of the machine. On the shaft 91 is mounted a multiple pulley 93 of stepped diameters and which are adapted to selectively receive a belt 94 which drives a multiple pulley 95 of diameters reversely stepped to those of the pulley 93 thus effecting a variable speed drive. The pulley 95 is freely rotatable on a shaft 96 and is adapted to be clutched to said shaft to drive the same by means of a clutch disc 97 fixed to the shaft provided with a leather or other desired friction contact or surface 98 so that when the pulley 95 is moved against the clutching face the shaft 96 will be driven. The shaft 96 is mounted in suitable bearings 99 on the frame of the machine. In order to produce clutching action, the pulley 95 has a slot 100 for reception of the bifurcated arm 101 of a bell crank lever mounted on a pivot 102 and with its other arm 103 connected to a spring 104 which normally maintains the clutch disengaged. A link 105 is connected to the lower end of an arm 106 fixed to the shaft 64. Thus when the treadle 69 is depressed it will produce oscillation of the treadle shaft 68, the arm 67, and arm 65 through the connecting link 66, which arm 65 will oscillate, the shaft 64 and through the arms 106 link 105 and bell crank lever arms 103 and 101 about the shaft 102 to produce clutching action, and at the same time through the respective linkages render the weight action on the upper roll operative as well as lowering the tape contact with the solvent applicator.

The shaft 96 supplies the power for driving the

sealing rolls and the connection therebetween is provided by means of a beveled gear 107 on the end of the shaft 96 which meshes with a beveled gear 108 on the vertical shaft 109 having worms 110 and 111 which engage and drive gears 112 and 113 mounted on the lower and upper roll shafts 13 and 12, respectively. The shaft 109 has its lower end supported by bearing 114 on an angle iron strip 115 secured to the frame 10 of the machine, and its upper portion supported by a bearing 116 which is mounted on the connecting member 18 for the brackets 15 and 16. From the foregoing it will be readily understood that the machine consists of a frame on 15 which is mounted a pair of sealing rolls, one above the other, and an adjacent table for the work. The sealing rolls are adapted to be heated to the desired temperature, and the mounting of the upper roll is of a character to 20 permit it to be urged toward the lower roll with a predetermined pressure, depending upon the characteristics of the material treated, including its thickness, hardness, and the like. Normally it is desirable that the upper roll exert pressure 25 on material passing between the rolls only when the rolls are rotated. However, under certain conditions it is desirable that the rotation of the rolls be stopped without releasing the pressure therebetween. An instance of the latter 30 condition occurs when it is desired to unite a second seam with the seam being formed as, for instance, when making a garment such as a rain-coat it becomes necessary to unite one piece of material with a seam already formed therein 35 with the material upon which a seam is being formed, which of course means that at the point of intersection of the seams the total thickness of the material is increased by the number of thicknesses occurring at the intersecting seam. It 40 is desirable at this point to stop the rotation of the rolls in order that the seams may be properly located with respect to each other and it is further desirable that pressure between the rolls be maintained in order that the pieces al- 45 ready between the rolls maintain their original relationship. In order to obtain this operation, the control mechanism for the roll driving clutch and for the pressure applying means is constructed in such a manner that partial release 50 of the treadle 69 will disengage the clutch, thus stopping the rolls, but will not release the pressure producing mechanism, whereas full release of the treadle 69 disengages the clutch and releases the pressure producing mechanism. The 55 construction also includes mechanism for using tape including the applying of a solvent to the tape, folding of the tape upon itself so that it may receive the superposed edges of sheets to be connected by integration of their edges with the 60 folded edges of the tape and without the sheets being directly joined, one to the other. Also the tape is not permitted to remain in contact with the solvent applicator at all times but only during such times as the rolls are rotating and 65 any work between them is advancing. In order to simplify and facilitate the handling of the work or the material to be joined, a table is mounted on the frame adjacent the rolls at substantially the same level, and it may have an extension or 70 apron 30' in front of the rolls to form a support for the work, and is provided with conveyor belts spaced longitudinally across the same and transversely of the frame of the machine so that when the work is fed to the rolls it will be 75 a simple matter to have it carried by the con-

veyors longitudinally of the table top and transversely of the machine frame.

The machine is so constructed that its operation is simple, a pair of switches being conveniently located at the front of the machine for supplying electrical energy to the heating rolls as well as to the driving motor and the operating treadle is relatively broad and wide, conveniently located for easy manipulation by the foot of the operator, and it is a simple matter to join thermoplastic sheets or other bodies by the application of heat and pressure, the rolls being relatively separable due to the mounting of the shaft to the upper rolls to permit material of different thicknesses to pass therebetween so that the serrated surfaces of the rolls may operate thereupon.

It will be obvious to those skilled in the art that various changes may be made in the invention without departing from the spirit and scope thereof and therefore the invention is not limited by that which is shown in the drawing and described in the specification but only as indicated in the appended claims.

What is claimed is:

1. Seamer rolls, heaters for said rolls, a portable frame supporting said rolls, a motor on said frame for driving said rolls, transmission elements between said motor and said rolls, said transmission elements including first and second shafts rotatably mounted on said frame, a series of pulleys on each of said first and second shafts, the pulleys on said first shaft having stepped diameters, opposite reversely stepped diameters on said second shaft, a belt for transmitting power from one of the pulleys of the first shaft to the proper pulley of the second shaft, means for driving said first shaft directly from the motor, means for driving said rolls from said second shaft and including a gear on said second shaft, a clutch member for engaging one of the pulleys on said second shaft for clutching and declutching said gear and pulleys, a second gear engaging said first gear, a worm shaft driven by said second gear, a pair of spaced worm gears on said worm shaft, a gear on each roll shaft driven by said last-mentioned gear, a bell crank clutch operating lever mounted on a vertical axis, additional lever means including arms disposed substantially at right angles and mounted on a substantially horizontal axis, a link connecting said levers, a treadle, a link connecting said treadle with the lever means disposed on said horizontal pivot, pressure structure for applying pressure between said rolls and means connecting said treadle and said pressure structure whereby upon complete release of said treadle said clutch will be disengaged and said pressure structure will be rendered inoperative thereby relieving pressure between said rolls and whereby upon partial release of said treadle said clutch only will be disengaged, thus stopping rotation of said rolls by maintaining pressure therebetween.

2. In combination a pair of rolls, heating elements for said rolls, a frame supporting said rolls, a motor on said frame for driving said rolls, transmission elements between said motor and said rolls, said transmission elements including first and second shafts rotatably mounted on said frame, a series of pulleys on each of said first and second shafts, the pulleys on said first shaft having stepped diameters, opposite reversely stepped diameters on the pulleys on said second shaft, a belt for transmitting power from one of the pulleys of the first shaft to the proper pulley of the second shaft, means for driving said first shaft directly from the motor, means for driving said rolls from said second shaft and including a gear on said second shaft, a clutch member for engaging one of the pulleys on said second shaft for clutching and declutching said gear and pulleys, a second gear engaging said first gear, a worm shaft driven by said second gear, a pair of spaced worm gears on said worm shaft, a gear on each roll shaft driven by said last-mentioned gear, a bell crank clutch operating lever mounted on a vertical axis, additional lever means including arms disposed substantially at right angles and mounted on a substantially horizontal axis, a link connecting said levers, a treadle, a link connecting said treadle with the lever means disposed on said horizontal pivot, pressure structure for applying pressure between said rolls and means connecting said treadle and said pressure structure whereby upon complete release of said treadle said clutch will be disengaged and said pressure structure will be rendered inoperative thereby relieving pressure between said rolls and whereby upon partial release of said treadle said clutch only will be disengaged, thus stopping rotation of said rolls by maintaining pressure therebetween.
